ATTORNEY

UNITED STATES PATENT OFFICE

BENJAMIN A. MOELLER, OF SAN DIEGO, CALIFORNIA

BEDCOVER-HOLDING DEVICE

Application filed May 9, 1927. Serial No. 189,977.

My invention relates to and has for a purpose the provision of a simple, inexpensive and durable device which is capable of ready application to any conventional form of bed 5 for holding the covering thereof in place against pulling loose at the foot of the mattress and thus exposing the feet of the occupant.

It is also a purpose of my invention to provide a cover holding device which functions to render available as bed covering the entire length of the blanket and other such coverings, whether single or double length, by eliminating the necessity of tucking the covering beneath the foot of the mattress.

I will describe only one form of bed cover holding device embodying my invention, and will then point out the novel features thereof in claims.

20 In the accompanying drawings,

Figure 1 is a view showing in top plan one form of bed cover holding device embodying my invention in applied position to a bed spring, the latter being shown in dash lines;

25 Figure 2 is an enlarged fragmentary vertical sectional view taken on the line 2—2 of Figure 1 and showing the device in applied position to a mattress and the bed covering therefor;

30 Figure 3 is an enlarged fragmentary plan view of the device in applied position to a bed spring;

35 Figures 4 and 5 are sectional views taken on the lines 4—4 and 5—5, respectively, of Figure 3.

Referring specifically to the drawings, my invention, in its present embodiment, comprises a bed covering engaging member designated generally at M and constructed, in the 40 present instance, of a single length of rigid material, such as steel or the like bent to form an elongated yoke corresponding in length to the width of the bed covering to which it is applied. Specifically, the member M comprises a rail 15 terminating at its ends in rounded portions 16, and the extremities of the rounded portions are bent laterally and split to provide hooks 17.

For securing the member M against movement in any position which will interfere

with its function of properly holding the bed clothing against being pulled loose at the foot of the mattress, I provide a pair of straps 18 formed of fabric or any other suitable material which are adapted to be applied longitudinally to the frame F of a bed spring. A third strap 19 is adapted to be applied transversely to the spring frame F and in intersecting relation to the straps 18 at points adjacent the foot end of the spring frame. The 55 several straps are looped at their ends and provided with buckles 20 by which they may be secured to the spring frame. At the points of intersection the strap 19 is stitched or otherwise secured to the straps 18, and short 60 lengths of straps 21 are secured to the strap 18 to form loops through which the hooks 17 are extended.

Such an arrangement of straps when associated with the spring frame F function to secure the member M against displacement longitudinally and transversely of the bed spring so that it is securely held in position to maintain the bed covering against pulling loose 70 from the foot of the mattress when the covering is in applied position to the member.

In Figure 2, I have shown the member M in applied position to a double length blanket B, the rail 15 being extended through the folded end of the blanket so as to hold such 75 end just beneath the foot end of the mattress. With the member M so applied, it will be manifest that pulling of the blanket upwardly toward the head end of the mattress will be ineffective to disengage it from the member M and, consequently, the blanket will be held against pulling loose at the foot of the mattress. When the blanket B is superimposed on or used as an enclosure or envelope 80 for the other bed covering, it will be clear 85 that it will function to prevent the other covering from pulling loose at the foot of the mattress. It is important to note that my device is such as to eliminate the necessity of tucking the blanket B, as well as the other 90 covering, beneath the foot of the mattress, thereby permitting the entire length of all of the coverings to be utilized.

Although I have herein shown and described only one form of bed cover holding 100

device embodying my invention, it is to be understood that various changes and modifications may be made therein without departing from the spirit of the invention and the spirit and scope of the appended claims.

5. I claim as my invention:

1. In a bed cover holding device, an elongated yoke having rounded ends terminating in laterally disposed extremities, said extremities being split and spread to form hooks.

10. 2. In a bed cover holding device, an elongated yoke having rounded ends terminating in laterally disposed extremities, said extremities being split and spread to form hooks, a pair of straps, and a third strap intersecting the first straps and secured to the latter at the points of intersection, and loops on the third strap in which said hooks engage.

15. 3. A bed cover holding device comprising an elongated bed covering engaging member having laterally extending ends provided with hooks, a plurality of straps adapted to extend longitudinally and substantially the full length of the bed spring for connection thereto, and another strap intersecting and secured to the plurality of straps and having means with which said ends of the member have hooked engagement.

20. 4. In a bed cover holding device, an elongated yoke having rounded ends terminating in laterally disposed extremities provided with hooks, a pair of straps, a third strap intersecting the first straps and secured to the latter at the points of intersection, and loops on the third strap in which said hooks engage.

25. 5. A bed cover holding device capable of being wholly interposed between a mattress and a bed spring comprising an elongated rigid bed covering engaging member of such length as to be capable of extending substantially the full width of a bed, a plurality of straps capable of extending substantially the full length of the bed and having means by which their ends are rendered capable of being secured to the bed spring, another strap intersecting and secured to said straps and having means by which its ends are rendered capable of being secured to the bed spring, and co-acting means on the member and straps for retaining the member against movement relative to the straps.

30. 6. A bed cover holding device comprising a plurality of non-rigid members capable of extending longitudinally and substantially the full length of a bed and having means by which their ends are rendered capable of being secured to the ends of a bed spring, a non-rigid member spanning and secured in substantially right angular and intersecting relation to the plurality of members and having means by which the ends thereof are rendered capable of being secured to the sides of the bed spring, an elongated rigid bed

covering engaging element capable of extending substantially the full width of the bed, and means for securing said element to said members, whereby the element will operate to hold the bed covering against withdrawal from the foot end of the mattress.

35. 7. A bed cover holding device comprising a plurality of straps adapted to extend longitudinally of a bed and having means by which their ends are rendered capable of being secured to the bed spring, a strap secured in intersecting relation to the plurality of straps and having means by which its ends are rendered capable of being secured to the bed spring, a rigid bed covering engaging element capable of extending substantially the full width of the bed, and co-acting means on the element and members for securing the former to the latter against movement longitudinally and transversely of the bed, whereby the element will operate to hold the bed covering against withdrawal from the foot end of the mattress.
